EXTRACTION OF HYDROCARBONS FROM
NATURAL GAS

David G. Brandt, Westfield, N. J., assignor to
Cities Service Oil Company, New York, N. Y.,
a corporation of Pennsylvania

Application October 9, 1940, Serial No. 360,401

10 Claims. (Cl. 196—8)

This invention relates to the extraction of hydrocarbons from high pressure gas and the separation and stabilization of the hydrocarbon products recovered.

More particularly the invention relates to the extraction of hydrocarbon distillates from high pressure gas wherein the gas is removed from the earth under its natural high pressure, the hydrocarbons extracted, and the pressure of the gas again built up to be recycled back into the earth formation or into a place for utilization.

Distillate pools have been discovered among the petroleum formations wherein a hydrocarbon distillate, in sand beds varying from ten to hundreds of feet in thickness, is associated with high pressure natural gas. The natural gas sand pressure may vary from 2,000 to 6,000 pounds per square inch or higher and the distillate usually exists in the vapor state. Often this distillate occurs in sufficient quantities to make it economically feasible to distil or scrub it out of the sand formation. This operation consists in maintaining the pressure on the sands, circulating the gas from the distillate beds to an extraction apparatus where the hydrocarbon distillates are separated from the gas and then the gas is recompressed and pumped back into the sand formation without materially reducing the pressure of the gas in the sands. This operation is carried out in a continuous cycle whereby the gas is continuously circulated in a closed cycle and the minimum amount of gas is removed in the extracting step of the cycle. By maintaining the pressure at substantially the natural rock pressure the maximum amount of hydrocarbons may be extracted from the pool.

The hydrocarbon distillates which occur in the earth are mostly hydrocarbons which are not liquid at normal temperatures and pressures, such as methane, ethane, propane and butane, but the distillate also contains some hydrocarbons, such as pentane and hexane, and may have an end boiling point of from 530° to 650° F. or higher. Many of these hydrocarbons are contained in gasoline and therefore the distillate is utilized principally for the manufacture of gasoline. Usually ethane will not be extracted from the gas because it is desirable to utilize the ethane in holding up the rock pressure. However, the propane and butane contents may have sufficient value to be extracted. In many cases, however, the propane and part of the butane will be returned to the sand formations for repressuring.

The extraction of hydrocarbon distillate from high pressure gas is very difficult because the natural pressure of the gas is above the critical

pressures of the hydrocarbon constituents and under these conditions the gas or hydrocarbon vapors in the gas do not act in accordance with well known gas laws. The densities of the hydrocarbons in the vapor state become equal to or greater than the same vapors in the liquid state and the heats of vaporization of the hydrocarbons at the critical temperature and pressures become, or approach zero.

Some hydrocarbon distillate is extracted from high pressure gas by retrograde condensation. The retrograde condensation is that condensation of hydrocarbons which takes place in the high pressure gas as the gas pressures are varied when the temperature is above the critical temperature. For example, high pressure gas from a well may be materially cooled and then, by dropping the pressure, a substantial amount of condensation of hydrocarbons will occur. The efficiency of retrograde condensation for extracting hydrocarbons from high pressure gas is not very high and this efficiency varies appreciably as the composition of the hydrocarbons in the gas varies.

A dry gas is commonly referred to as a gas which does not contain hydrocarbons in the gasoline boiling point range. At the present time, however, dry gas usually is made up of methane and ethane wherein the methane content varies from 80 to 99% of the mixture. The C₁ and C₂ hydrocarbons are herein referred to as "undesired hydrocarbons" and in some cases C₃ and C₄ hydrocarbons may be undesired hydrocarbons. The C₃ hydrocarbons, such as propane and propylene, and C₄ hydrocarbons are now being quite extensively used in the industry. The C₄ and higher hydrocarbons and often the C₃ and C₄ hydrocarbons are extracted from the gas according to this invention and are herein referred to as "desired hydrocarbons." In a gas absorption system therefore, it may be desirable to carry on the absorption so as to remove from the gas all hydrocarbons heavier than methane and ethane, or C₁ and C₂ hydrocarbons. When the absorption is being carried on the absorption oil is preferably saturated with all of the various hydrocarbons in the natural gas. An absorption oil, such as high boiling gasoline, kerosene, or gas oil, is selective in its operation in that it tends to absorb the C₃ to C₈ hydrocarbons and to reject the C₁ and C₂ hydrocarbons. Furthermore, the vapor pressures of the C₁ and C₂ hydrocarbons are so high that if the absorption is carried out at a comparatively low pressure (100 to 200 lbs.) the amount of C₁ and C₂ hydrocarbons absorbed is comparatively small. However, as the

absorption operation is carried on at high pressures (1000 to 2000 lbs.) the amount of C₁ and C₂ hydrocarbons absorbed in the absorption oil becomes quite large because these absorption oils can hold or absorb much more of these lighter hydrocarbons at the higher pressures. Furthermore the densities of the lighter hydrocarbon vapors become comparatively high at the high pressures.

In a recycling process it is important that the absorption of the hydrocarbons from the natural gas should be carried out at as high pressure as the process will be efficient and selective. The higher the absorption pressure the less compression will be required to recompress the treated gas to a point above the earth formation pressure in order that the gas may be returned to the earth.

The hydrocarbon distillate which is removed by absorption contains a large amount of low boiling hydrocarbons, such as C₁, C₂ and C₃ hydrocarbons, that must be removed in order to make a marketable gasoline from the distillate. This process is usually defined as "gasoline stabilization." The low boiling hydrocarbons removed in the distillate extraction process should be held at a minimum in order to prevent a reduction in pressure in the oil sands in the gas repressuring or recycling operation. Accordingly it is desirable to carry on the absorption operation in the extraction of the hydrocarbon distillate to remove the minimum amount of undesired hydrocarbons or gases which are to be pumped back to the distillate pool for scrubbing out the distillate.

One object of the present invention is to carry out the absorption of the hydrocarbon distillate in a high pressure absorption process in a selective manner to reject undesired hydrocarbons while efficiently recovering the desired hydrocarbons.

In accordance with this object one feature of the invention consists in conditioning the lean absorption oil by saturating it with the low boiling undesired hydrocarbons to such a point that a very small amount of undesired hydrocarbons will be absorbed by the oil in the main absorption system. This permits practically all of the undesired hydrocarbons to be recompressed and returned to the earth formation for maintaining the desired high rock pressure. Further by carrying on the absorption under a high pressure the return of the gas to the earth can be accomplished with the use of the minimum amount of mechanical recompression.

Another object of the invention is to presaturate the absorption oil used for recovering the hydrocarbons with undesired hydrocarbons under high pressures approaching the absorption pressure whereby the absorption of undesired hydrocarbons in a high pressure absorber will be substantially avoided.

With these and other objects and features in view, the invention consists in the gasoline extraction process herein described in detail and particularly defined in the claims.

The drawing is a flow sheet of an apparatus for carrying out the absorption system of the present invention in its preferred form.

Referring to the drawing the preferred form of the process may be outlined as follows:

High pressure gas, which may be natural gas from the earth formation and in which may be included liquid hydrocarbons that have been condensed by retrograde condensation, is intro-

duced into an absorber 10 through a line 12. The gas may be at the natural rock pressure of the pressure of the gas may be reduced in effecting retrograde condensation. In any case, however, the absorption in the absorber 10 is carried out under a high pressure of 1200 to 2000 lbs. so that a valve 14 in the line 12 is provided for controlling the pressure in the absorber. The gas passes through the absorber 10 countercurrent to the flow of absorption oil which is introduced at the top of the tower through a line 16. Dry gas is removed from the top of the absorber and this gas then passes through one or a series of compressors 18 where it is recompressed to a pressure above the rock pressure so that it may be recycled back into the earth. The absorption pressure preferably should be as high as possible, particularly for a gas recycling operation, to reduce the cost of repressuring the gas for return to the earth formation or to the place of utilization. This pressure is controlled by and limited to those densities and partial pressures of the gas which will not act to carry the absorption oil out of the tower during the countercurrent circulation of the gas and oil in the tower. When treating a gas containing 90 percent methane, pressures as high as 2000 lbs. may be used in the absorption.

Although the gas entering the absorption tower 10 may preferably come directly from the well, the present invention contemplates the use of retrograde condensation along with absorption for the extraction of hydrocarbon distillate from the natural gas. Preferably the retrograde condensation is carried out before the gas enters the absorber 10. Preferably the retrograde condensate after being produced is not separated from the gas but passes in admixture with the gas directly into the absorber 10. In case retrograde condensation is carried out it may not be necessary to use the valve 12 to regulate the pressure of the gas for the absorption operation. The retrograde condensate may be produced by cooling and reducing the pressure of the gas under retrograde condensing conditions.

The present process is carried out to separate from the gas being treated only the desired hydrocarbons, that is hydrocarbons having a molecular carbon content of C₃ and higher. In some cases the desired hydrocarbons may be C₄ and higher and the process is controlled to selectively reject the undesired hydrocarbons which may be C₁ and C₂, C₁ to C₃, or C₁ to C₄ hydrocarbons. The selective absorption is accomplished by presaturating the absorption oil which enters the tower 10 through the line 16 with the undesired hydrocarbons. This presaturated oil then rejects substantially all undesired hydrocarbons in the gas being treated. The amount of absorption oil used is controlled so that substantially all of the desired hydrocarbons will be absorbed and at the same time the partial pressures of all of the hydrocarbons absorbed in the absorption oil will be such as to reject the undesired hydrocarbons while retaining all desired hydrocarbons. The rejected, undesired hydrocarbons pass out of the tower 10 to a compressor 18 to be recompressed so that they may be recycled back to the earth reservoir or to a point of utilization.

In order to separate the desired hydrocarbons from the undesired hydrocarbons in the absorption oil, the absorption oil is subjected to distillation or stabilization to selectively remove the undesired hydrocarbons at high pressure.

These undesired hydrocarbons may be absorbed in lean absorption oil for the purpose of pre-saturating the lean absorption oil preparatory to introducing it into the primary absorption tower.

To this end rich absorption oil (absorption oil saturated with gas hydrocarbons) leaves the bottom of the primary absorber 10 through a line 20 and passes through a pressure reducing valve 22 into a stabilizer 24. The lower pressure in the stabilizer 24 tends to release undesired hydrocarbons, such as methane, ethane, and if undesired, propane, and these vapors rise through the tower to be separated from the absorption oil. To carry on the separation, the absorption oil in the bottom of the stabilizer is circulated through a line 26 to a reboiler 28 from which vapor returns by line 30 to the stabilizer. This heating operation is carefully controlled in conjunction with the pressure reduction to act to free undesired hydrocarbons from the absorption oil. As the undesired hydrocarbon vapors pass upwardly through the stabilizer tower they pass in countercurrent circulation to condensed hydrocarbons for the purpose of scrubbing from the vapors any desired hydrocarbon vapors that may be set free in the bottom of the tower. The stabilizing tower may be a filled tower, a bubble cap tower, a plate contact tower, or any of the approved types of fractionating equipment. The reflux for carrying on the fractional distillation operation in the tower 24 is obtained by passing hydrocarbon vapors flowing through the tower 24 through a line 32 to a cooler 34. Part of the hydrocarbon vapors are condensed in the cooler 34 and pass into a receiver 36. Condensate passes from the receiver 36 through a line 38 to a distributor 40 located in the top of the stabilizer. The amount of condensate returning to the top of the tower is controlled by means of a valve 42, which in turn, is controlled by a thermostat 44 positioned in the vapor in the line 32. The amount of condensate returned to the top of the stabilizer, therefore, will depend upon the temperature of the vapors in line 32, and on the temperature of the condensate which, in turn, will depend upon the temperature of the water or cooling medium used in the cooler 34. Uncondensed, undesired hydrocarbon gases which pass through the cooler 34 flow into the receiver 36 and pass from the receiver 36 through a line 45 into the bottom of an absorption tower section 46 located on the top of the stabilizer 24. The stabilizer section is separated from the absorber 44 by means of a solid partition 47. The line 45 is preferably used as an overflow line so that if more condensed undesired hydrocarbons are collected in the receiver 36 than are required as reflux in the stabilizer 24, this condensed hydrocarbon distillate will flow from the receiver 36 into the bottom of the absorber 46 to be mixed with the absorbing oil, as hereinafter described.

With a high pressure system, the hydrocarbon separated from the absorption oil in the stabilizer 24 will be a portion of the undesired hydrocarbon and be principally methane and some ethane. To further separate undesired hydrocarbons the rich absorption oil is distilled in a second stage. To accomplish this, oil from the reboiler 28 passes through a line 48 in which its pressure is reduced by a valve 50. The oil passing through the line 48 enters the bottom of a second stage stabilizer 52. The stabilizer 52 is operated similarly to the operation of the stabilizer 24 in that the absorption oil passes through

75 a line 54 to a reboiler 56 from which vapors pass through a line 58 into the stabilizer 52. The vapors set free in the stabilizer pass upwardly through filling in the stabilizer countercurrent to reflux condensate introduced through a distributor 60 located at the top of the stabilizer. This condensate is produced by condensing hydrocarbon vapors which pass through a line 62 to a cooler 64. Condensed hydrocarbon vapors enter a receiver 66 and flow back through a line 68 to the distributor 60. The return of condensate to the distributor 60 is controlled by a thermostatic valve 70 which controls the amount of condensate returned depending upon the temperature of the vapors flowing through the line 62, the amount returned also depending upon the temperature of the condensate. Uncondensed vapors accumulating in the receiver 66 pass through a line 72 into the bottom of an absorber tower section 74 positioned on top of the stabilizer 52 above a solid partition 76. Any excess hydrocarbon distillate accumulating in the receiver 66 above that required for reflux in the stabilizer 52 passes through the line 72 along with the vapors and mixes with the absorption oil in the bottom of the absorber 74.

Depending upon the pressure at which the primary absorber is operated two or more stages of stabilization may be required for separating the undesired hydrocarbons from the desired hydrocarbons. The number of stabilizers required, however, depends more directly upon the pressure being used and upon the desired degree of presaturation of the absorption oil with the undesired hydrocarbons before the absorption oil is returned to the primary absorption tower. If the primary absorption is carried out at pressures from 1200 to 1600 lbs, three stages of stabilization may be effectively used.

40 To effect a further separation of the undesired hydrocarbons from the rich absorption oil, the oil is passed through a line 78, through a pressure reducing valve 80 to the lower portion of a third stage stabilizer 82. The absorption oil is heated 45 in the lower portion of the stabilizer 82 by passing oil through a line 84 into a reboiler 86 and passing vapors through a line 88 to the stabilizer. In the illustrated apparatus substantially all of the remaining undesired hydrocarbons which are 50 not condensable at the existing pressure are separated from the absorption oil in the stabilizer 82. The vapors rising through the stabilizing tower pass through a condensate distributor 90 positioned in the top of the stabilizer. This condensate 55 is produced from vapors passing through a line 92 to a cooler 94 where vapors are condensed, the condensate being collected in a receiver 96. The condensate flows from the receiver through a line 98 back to the distributor 90. The amount of condensate returned to the stabilizer is controlled by a thermostatic valve 100 which controls the flow depending upon the 60 temperature of the vapors passing through the line 92. Uncondensed gases collecting in the receiver 96 pass through a line 102 into the bottom of an absorber tower section 104 positioned on the top of the stabilizer 82 and separated therefrom by a solid partition 106. Any condensate 65 accumulating in the receiver 96 which is not returned to the stabilizer 82 flows through the line 102 to be mixed with absorption oil in the bottom of absorber 104.

When the mixture of absorption oil and distillate has been stabilized to separate the non-condensable undesired hydrocarbons this mixture is

then passed through a line 108, provided with a pressure reducing valve 110, into a still 112. In this still desired hydrocarbons are driven overhead and lean absorption oil removed from the lower portion of the still. To carry on the distillation, oil from the still is removed through line 114 and passed into a reboiler 116, from which vapors pass through a line 118 back to the still. Vapors of the desired hydrocarbons distilled off in still 112 pass through a line 120 into a condenser 122 and then into a receiver 124. A safety valve 126 is preferably mounted in a gas line at the top of the receiver 124 to control the discharge of gas therefrom.

It is not essential to operate the stabilizing towers in order to separate all of the undesired hydrocarbons from the mixture of desired hydrocarbons and absorption oil. It is necessary only that all non-condensable undesired hydrocarbons should be separated by the time the oil has passed through the lowest pressure stabilizer 82 and any undesired hydrocarbons that are condensable may be carried over to the still 112 and these hydrocarbons will be condensed and collected in the receiver 124.

The condensed desired hydrocarbons are further stabilized, particularly when manufacturing gasoline, in order to obtain a product of the desired vapor pressure. To accomplish this, condensate from the receiver 124 passes through a line 128, and is forced by means of a pump 130 through a heat interchanger 132 into a stabilizer 134. In normal operation, the still 112 would be operated at a pressure of approximately 100 lbs. per square inch while the gasoline stabilizer 134 would preferably be operated at a pressure of from 200 to 400 lbs. To assist in the stabilization the desired product is passed from the bottom of the stabilizer 134 through a reboiler 136. Light hydrocarbons driven off overhead in the stabilizer 134 pass through a vapor line 138 to a condenser 140 and then into a receiver 142. A pressure control valve 144 is mounted in the gas discharge line from the receiver 142. The cooling by the condenser 140 is controlled by a pressure operated valve 146 which control is based upon the pressure in the receiver 142. The desired product, or hydrocarbons, which is, for example, a stabilized gasoline is removed through a cooler 148 and passes through a line 150 to storage.

The distillation in the still 112 acts to force the desired hydrocarbons, such as gasoline, overhead and the higher boiling absorption oil is held in the still. This higher boiling product is the absorption oil and may contain all hydrocarbons between the end boiling point of gasoline and the end point of the heavy ends of the distillate removed from the gas which may be up to 650° F. This absorption oil distillate is removed from the still 112 through a line 152 and passes through an interchanger 132 from which it is forced by means of a pump 154 through a line 156 into the top of absorber 104. Practically all of the absorption oil remains in cyclic circulation so that a portion of the high boiling distillate removed from the gas may be drawn out of the line 156 through a valved line 155 to pass to storage.

The operation of the pump 154 is such as to raise the pressure of the absorption oil to a pressure only slightly lower than that being maintained in stabilizer 82. As the absorbing oil passes downwardly through the absorber 104 it comes into countercurrent contact with undesired hy-

drocarbons entering the bottom of the absorber through the line 102. The absorption oil will take up the undesired hydrocarbons entering the absorber 104, and the resulting absorption oil collecting in the bottom of the absorber 104 is then passed to the next higher pressure stage for absorption of undesired hydrocarbons in that stage.

When two or more stabilizers are used for separating the undesired hydrocarbons from the desired hydrocarbons it is not necessary to separate any one specific light hydrocarbon in a single stabilizer, but a mixture of the lighter undesired hydrocarbons may be separated in each stabilizer and a sufficient number of stabilizers used so that all of the noncondensable undesired hydrocarbons will be removed by the time the rich absorption oil has passed through the last stabilizer. The larger number of stabilizers aids the operation of the stabilizers so that latitude can be given in the temperatures and pressures in the stabilizers in order to effectively remove all of the undesired hydrocarbons by the time the rich oil has passed through the last stabilizer.

The lean absorption oil introduced into the absorber 104 is cool and may act as a condensing medium when absorbing the light hydrocarbons therein. If the absorption is carried too far the pressure in the absorber will tend to fall and thus upset the operating condition in the stabilizer 82. To avoid this condition a bypass line 158 controlled by a valve 160 is connected with the line 156, by which lean absorption oil may be bypassed around the absorber 104. The valve 160 is connected through line 162 with the stabilizer 82 so that the pressure in the stabilizer can be used to control the amount of liquid passing through the bypass line 158. If the pressure falls below a predetermined point the valve will open.

The light hydrocarbons which are separated from the desired hydrocarbons in the gasoline stabilizer 134 collect in receiver 142. This product is preferably returned to the lean absorption oil by means of a pump 164 and line 166, the pump 164 being operated to raise the pressure of the light hydrocarbon distillate to the pressure prevailing in the absorber 104, and this distillate is introduced through the line 166 into the bottom of the absorber.

The absorption oil which has absorbed the undesired hydrocarbons from the stabilizer 82 and the stabilizer 134 flows from the bottom of the absorber 104 through a line 168, through a cooler 170, to a pump 172 which forces the oil through a line 174 into the top of the absorber 14. The oil passing through the line 168 may contain absorption oil which passes through the by-pass line 158. In the absorber 14 the absorption oil passes countercurrent to the undesired hydrocarbons separated in the stabilizer 52, this absorption being carried on at about the pressure which is maintained in the stabilizer 52.

The pressure in the stabilizer 52 and absorber 14 is controlled similarly to that on the stabilizer 82. A by-pass line 176 controlled by a pressure operated valve 178 will permit oil to be bypassed around the absorber 14 in order to prevent the drop of the pressure therein.

The partially saturated lean absorption oil flows from the bottom of the absorber 14 through a line 180, through a cooler 182 to a pump 184 which forces the cool oil through a line 186 into the top of the absorber 46, the operation of the pump being such that the oil will be introduced

into the absorber 46 at about the pressure prevailing in the stabilizer 24. The lean absorption oil passing downwardly through the absorber 46 passes countercurrent to rejected undesired hydrocarbons removed by the stabilizer 24. The bypass line 176 is connected with the line 180 to permit the lean absorption oil to flow around the absorber 74. The pressure in the absorber 46 is maintained or controlled by a bypass line 188 having a pressure controlled valve 190 therein. The valve 190 is connected with the stabilizer 24 to control the bypass line in accordance with the pressure in the stabilizer 24. The line 188 connects with a line 192 by which presaturated absorption oil flows from the absorber 46 through a cooler 193 to a pump 194 for forcing the presaturated oil through the line 16 into the top of the primary absorber 10.

The operation of the absorber units 46, 74 and 104 is preferably carried on so that all of the lean absorption oil which is introduced into the primary absorber will be saturated with hydrocarbons of the type of the undesired hydrocarbons. To accomplish this the lean oil has been freed of all light hydrocarbons prior to being introduced into the first unit of the absorber system. The pressures in the absorbers 104, 74 and 46 are stepped up in stages to carry out the absorption at the highest practicable pressure in order to insure that the absorption oil will be saturated with the light undesired hydrocarbons. In the present invention three stabilizer towers are used for removing the undesired hydrocarbons and three absorbers are used for presaturating the absorption oil. If very high absorption pressures are used more stabilizer and absorption towers may be employed. On the other hand if lower pressures (800 to 1200 lbs.) are used two stabilizers and two absorption towers generally will be sufficient. By having the lean oil saturated with the light undesired hydrocarbons there will be substantially no absorption of the same type of light undesired hydrocarbons in the primary absorber. To assist in controlling the temperature and pressure in the stabilizers 24, 52 and 82, connections may be made to introduce fresh lean absorption oil directly into any of the absorbers 46, 74 or 104.

Presaturation tends to cut down the heat of solution in the primary absorber and therefore cuts down materially the amount of absorption oil required for separating the desired hydrocarbons from the gas. With the higher pressures in the primary absorber the heat of vaporization (or the heat of solution) of the gas hydrocarbons in the absorption oil approaches zero so that less cooling to take care of the heat of solution is required and less oil is necessary for the absorption.

As an example of an operation of the apparatus illustrated in the drawing the primary absorber 10 may be operated at 1600 lbs.; the first stabilizer may be operated at 1000 lbs., the second stabilizer at 700 lbs. and the third stabilizer at 300 lbs. The still 112 may be operated at approximately 100 lbs. and the gasoline stabilizer 134 operated at 300 lbs. In such an operation ethane and methane will be the undesired hydrocarbons and the C₃ and higher boiling hydrocarbons are the desired hydrocarbons.

While theoretically the system illustrated in the drawing might be used for giving a full presaturation of the lean absorption oil, practically this does not occur. Furthermore some of the light hydrocarbons will be exhausted through

control valves 196, 198 and 200 mounted respectively in gas discharge lines from the top of the absorption towers 46, 74 and 104. These valves furthermore operate in conjunction with the valves 190, 178 and 160 for controlling the pressures in the stabilizers 24, 52 and 82. The valves 190, 178 and 160 tend to maintain the pressure up to the desired maximum, while the valves 196, 198 and 200 tend to control the pressure if it exceeds a desired maximum.

When using the process described herein on a gas recycling system the amount of gas which would be exhausted through the valves 196, 198 and 200 should not be more than would be required for fuel to furnish the heat for operating the reboilers 28, 56, 86, 116, and 136. It will be seen furthermore that the absorption system does not require the use of compressors for compressing a large amount of residue gas from a low pressure up to high line-pressure. The undesired hydrocarbons are absorbed in the lean absorption oil and therefore they are brought up to the absorber pressures by means of liquid pumps, the operation of a liquid pump being relatively cheap compared to the operation of high pressure gas compressors.

In some cases where the rock pressure in the earth formation is reduced condensation of vapors occurs in the formation. Under such circumstances distillate is often carried out of the formation with the gas and taken to the absorption system. This distillate may also be supplemented by distillate condensed out of the gas by retrograde condensation. In the present process it is contemplated that the mixture of gas with distillate, whether the distillate is produced by condensation in the earth or by retrograde condensation after the gas is removed from the earth, shall be absorbed or mixed with the absorption oil and the mixture then treated to separate the absorption oil from the hydrocarbon mixture and then fractionate and stabilize the hydrocarbon distillates recovered.

Having thus described the invention what is claimed as new is:

1. A process of separating desired hydrocarbons from undesired hydrocarbons contained in gas comprising passing the gas through a hydrocarbon oil absorbing menstruum in a primary absorber maintained at a pressure above the critical pressure of the hydrocarbons being separated to absorb the desired hydrocarbons of the gas, continuously removing the rich absorption oil from the absorber and reducing the pressure of the oil in a succession of stages while heating the oil in each stage, controlling the pressure reduction and the heating of the oil in the stages to distil overhead substantially only the absorbed undesired hydrocarbons in each stage, removing undesired hydrocarbons from the absorption oil after the pressure has been reduced to provide a lean oil, passing the lean oil consecutively into and through a series of absorbers maintained at progressively higher pressures corresponding approximately to the pressures of the various stages in contact with the undesired hydrocarbons separated in the various stages to saturate the lean oil with the undesired hydrocarbons, and returning the resulting presaturated oil to the primary absorber to contact the gas therein.
2. A process of separating desired from undesired hydrocarbons contained in gas comprising passing the gas through a hydrocarbon oil absorbing menstruum in a primary absorber maintained at a high pressure to absorb the desired

hydrocarbons of the gas, continuously removing the rich absorption oil from the absorber and gradually reducing the pressure in a series of stages while heating the oil to separate only undesired hydrocarbons from the oil, separating and stabilizing desired hydrocarbons from the rich absorption oil after the pressure reduction, absorbing undesired hydrocarbons separated in each stage in relatively lean absorption oil in a corresponding absorption stage maintained at a pressure at least as high as the pressure of the stage in which the hydrocarbons were separated, lean absorption oil being introduced into the lowest pressure absorption stage and passed consecutively through said absorption stages to the highest pressure absorption stage of the series, and passing the presaturated absorption oil from the highest pressure absorption stage to the primary absorber to contact the gas therein.

3. A process of separating desired hydrocarbons from undesired hydrocarbons contained in gas comprising passing the gas through a hydrocarbon oil absorbing menstruum in a primary absorber, maintaining a high pressure in the absorber to saturate the absorbing oil with hydrocarbons of the gas, continuously removing the rich saturated oil from the absorber and reducing the pressure of the oil in a succession of stages while heating the oil in each stage to stabilize the absorption oil mixture, controlling the pressure reduction and the heating of the oil in each stage to distil overhead only the undesired absorbed hydrocarbons, removing desired hydrocarbons from the absorption oil after the pressure has been reduced, passing the lean absorption oil through absorbers in the successive stages and successively increasing the pressure on the lean oil as it advances through the absorbers in the respective stages to correspond to the pressures in the respective stages of the absorption oil stabilization, absorbing separated undesired hydrocarbons in the lean absorption oil in each stage and forcing the presaturated absorption oil from the highest pressure stage back to the primary absorber to be passed in contact with the gas introduced thereto.

4. The process defined in claim 2 wherein condensable low boiling hydrocarbons recovered in stabilizing the desired hydrocarbons is added to the lean absorption oil before it is introduced into the primary absorber.

5. The process defined by claim 1 wherein the amount of lean oil passing through the absorber in each stage is controlled by the pressure of the stage to maintain a predetermined maximum pressure therein.

6. The process defined by claim 1 wherein undesired hydrocarbon vapors that are not absorbed in the lean oil are expelled from the stage absorbers when the pressure tends to exceed a predetermined maximum.

7. The process defined in claim 3 in which the stabilization of the absorbed hydrocarbons is controlled to remove all undesired hydrocarbons which are non-condensable at the pressure at which the desired hydrocarbons are separated from the absorption oil by distillation.

8. In a process for separating and recovering desired hydrocarbons from a high pressure gaseous mixture in which the mixture is subjected to pressure reduction to produce a retrograde condensate and in which the remaining portion of the gaseous mixture is subjected to the action of an absorption oil in an absorber for the recovery of further quantities of desired hydrocarbons, the

improvement which comprises passing the retrograde condensate with the remaining gaseous constituents at high pressure into the absorber and carrying out the absorption operation at high pressure, passing the resulting mixture of rich absorption oil and retrograde condensate through a series of rectifying zones of progressively decreasing pressure and removing an undesired gas fraction overhead from each zone, passing said overhead fractions into separate absorbers held at approximately the pressure under which the fraction is produced, passing a lean absorption oil into the absorber of lowest pressure and then in series through the said absorbers in contact with said overhead fractions to saturate the lean absorption oil, and introducing the saturated absorption oil into the first-mentioned absorber.

9. A process of separating desired hydrocarbons from undesired hydrocarbons contained in gas comprising passing the gas through a hydrocarbon oil absorbing menstruum in a primary absorber maintained at a high superatmospheric pressure to saturate the absorbing oil, continuously removing the rich saturated oil from the absorber and gradually reducing the pressure on the oil in a series of distillation stages while heating the oil to separate substantially only undesired hydrocarbons from the oil, separating and stabilizing desired hydrocarbons from the rich absorption oil after the pressure has been reduced to provide a lean absorption oil, successively absorbing undesired hydrocarbons separated in each stage in the lean absorption oil while conducting the lean absorption oil consecutively through a series of absorption stages, controlling the amount of absorption oil passing through the absorption stages and the pressure therein so that the absorption oil leaving the series of absorption stages will have absorbed enough of the undesired hydrocarbons to be substantially saturated, and forcing the substantially saturated absorption oil from said absorption stages into the primary absorber to be passed in contact with the gas therein.

10. In a process for separating and recovering desired hydrocarbons from a high pressure gaseous mixture in which the mixture is subjected to pressure reduction to produce a retrograde condensate and in which the remaining portion of the gaseous mixture is subjected to the action of an absorption oil in an absorber for the recovery of further quantities of desired hydrocarbons, the improvement which comprises passing the retrograde condensate with the said remaining portion of the gaseous mixture at high pressure into the absorber and carrying out the absorption operation at high pressure, subjecting the resulting mixture of rich absorption oil and retrograde condensate to a fractionating operation in a series of fractionating zones of progressively decreasing pressure in which the absorbed undesired hydrocarbons are separated out in the form of gas in each zone and passed in intimate contact with a lean absorption oil in separate absorbers, one of which is associated with each zone, to saturate the lean absorption oil with the undesired hydrocarbons, and introducing the resulting saturated absorption oil into said first-mentioned absorber to be brought in contact with the said remaining portion of the gaseous mixture, whereby the undesired hydrocarbons in the absorption oil introduced into said first-mentioned absorber are replaced.
